(57) **CLAIM**

The ornamental design for a pharmaceutical packaging, as shown and described.

DESCRIPTION

FIG. 1 is a bottom perspective view of a pharmaceutical packaging, showing our new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a bottom plan view thereof.

The broken lines are shown for the purpose of illustrating parts of the article that form no part of the claim.

The top plan view of the pharmaceutical packaging is not shown in the drawings or described in the specification and, therefore, forms no part of the claimed design.
